Williamson & Merchant

UNITED STATES PATENT OFFICE.

DELBERT E. BARTON, OF MINNEAPOLIS, MINNESOTA.

CULTIVATOR.

SPECIFICATION forming part of Letters Patent No. 670,093, dated March 19, 1901.

Application filed December 10, 1900. Serial No. 39,321. (No model.)

To all whom it may concern:

Be it known that I, DELBERT E. BARTON, a citizen of the United States, residing at Minneapolis, in the county of Hennepin and State of Minnesota, have invented certain new and useful Improvements in Cultivators; and I do hereby declare the following to be a full, clear, and exact description of the invention, such as will enable others skilled in the art to which it appertains to make and use the same.

My invention relates to cultivators and other tillage-machines, and has for its especial object to provide certain improvements in the devices for suspending the drag-bars and gangs of shovels or other tillage devices.

To this end my invention consists of the novel devices and combinations of devices hereinafter described, and defined in the claims.

The invention is illustrated in the accompanying drawings, wherein like notations refer to like parts throughout both views.

In said drawings, Figure 1 is a vertical longitudinal section showing a cultivator equipped with my improvements, some parts being omitted and others broken away; and Fig. 2 is a detail in section on the line $x^2 x^2$ of Fig. 1.

The fixed or main frame 1, the arch 2, the supporting-wheels 3, the drag-bars 4, coupled

30 to the main frame for vertical and lateral pivotal motion, the pivoted mast 5, the connecting pipe or bar 6, with its arm 7 engaging the claw or hook at the upper end of the mast, the hand-lever 8, pivoted to the arch 2 and 35 having an arm 9, connected to the cross-rod 10, carried by the brace-rods 11, which connect the same with the fixed frame 1, and the lock-segment 12 for coöperation with the lever 8 are all of the ordinary standard construction and serve the customary functions.

Having regard now to my improvements, I provide a two-armed rocker 13 and pivot the same to the fixed frame 1 in advance of the pivoted mast 5. This rocker 13 is connected 45 with the mast 5 by three flexible connections marked, respectively, 14, 15, and 16. The upper or top connection 14 to the mast is shown as in the form of a chain and bail hook and as connecting the upper end portion of the 50 rocker 13 with the upper end portion of the pivoted mast in any desired adjustment, according to the position of the bail-hook there-

on. The two bottom or lower end connections 15 and 16 are convergent and connect the opposite ends of the rocker 13 to the lower end portion of the pivoted mast 5, the connection to the mast being made on a common center 55 a. As shown, the connection to the mast 5 is made by means of a double hook 17, which is pivoted to the mast and the hook ends of 60 which engage with the inner ends of the convergent connections 15 and 16. The pivoted hook 17 may be applied to the mast 5 at any one of several different points of adjustment. One of the two lower or converging connections 65 15 and 16 must be elastic, and the elastic connection can occupy either position, according to whether the top connection 14 takes hold of the upper or the lower end of the rocker 13. As shown, the top connection 14 70 from the mast 5 takes hold of the upper end of the rocker 13, and hence the elastic member of the two bottom connections connects the mast with the lower end of the rocker. As shown, the elastic connection 16 is in the form of an 75 open-ended compressed spring, and the connection 15 is in the form of a chain, adapting the same to have any of its links engaged with the pivoted hook 17, thereby affording a means for adjusting the tension on the elastic member or spring 80.

With the elements 13 to 17, inclusive, applied as above described, it follows that all the strains which come from the drag-bars or shovel-gangs will be yieldingly taken on the 85 elastic member or spring 16 and in line with the axis thereof. When the machine is at work, for example, the parts will be in the position shown in full lines in Fig. 1, and in said working position the drag-bars or shovel-gangs are of course suspended from the pivoted mast 5, and said mast is held by the parts 90 13 to 17, inclusive, with freedom to move yieldingly backward whenever any special strain comes onto the shovels. For example, suppose that some of the shovels should run under some fixed obstruction, like a root, stump, or stone, or engage under a piece of tough sod, turf, or hard ground. Then a downpull will be produced on the shovels and rear ends of 100 the drag-bars under the forward draft from the animals, and the strain will be taken over the chain 14, the rocker 13, the spring 16, and the hook 17, and the strain so taken on the

spring 16 being applied thereto over the lower end of the rocker 13 will be taken endwise of the spring, on the axial line thereof, just as the balancing strain is taken when the parts 5 are in their normal working positions, as shown in full lines in Fig. 1. When the top of the rocker 13 moves backward from the down-pull on the shovels, the chain 15 of course slackens and the spring 16 is set under increased tension. When the shovels are disengaged from whatever caused the downpull, the spring 16 will automatically restore the parts to their normal or balanced working position. When the parts are raised into their idle position, as shown in dotted lines in Fig. 1, the distended spring 16 will contract, thereby throwing the upper arm of the rocker 13 forward and applying the tension of the spring over the chain 15 and through the hook 17 to the 10 pivoted mast 5, thereby causing the spring 16 to assist in the lifting action for raising the drag-bars at all points of the motion. If the parts 15 and 16 should be reversed in position and the top connection 14 from the 15 mast be connected to the lower end of the rocker 13, the general action would be the same in its effect on the drag-bars and shovels; but the rocker 13 would take the reverse motions in point of time or order, as compared with 20 those above described, as incidental to the positions occupied by the said parts 14, 15, and 16, as shown in the drawings.

By actual usage I have demonstrated the efficiency of the invention herein disclosed 35 for the purposes had in view.

When the drag-bars are raised into their idle position, as shown in dotted lines in Fig. 1, the pivoted mast 5 rests against a suitable stop 18, which is shown in Fig. 2. The "kick-off" is not shown.

What I claim, and desire to secure by Letters Patent of the United States, is as follows:

1. In a tillage-machine, the combination with a pivoted drag-bar and pivoted mast

from which the drag-bar is suspended, of a 45 two-armed rocker pivoted to the frame, and three flexible connections from said rocker to said mast, the top member of which connections connects one end of said rocker with the upper end portion of said mast, and the 50 two bottom members of which connections are convergent, and one thereof elastic, and connect opposite ends of said rocker to the lower end portion of said mast, on a common center, substantially as and for the purposes 55 set forth.

2. In a tillage-machine, the combination with a pivoted drag-bar and a pivoted mast from which the drag-bar is suspended, of a 60 two-armed rocker pivoted to the frame, an upper flexible connection from the upper end portion of the mast to one end of the rocker, two lower end flexible connections extending from opposite ends of said rocker, and a hook pivoted to the lower end portion of the mast 65 and engaging with the convergent ends of said two lower end connections, one of which lower end connections is elastic and takes hold of the rocker 13 at the end opposite to the top connection, substantially as described. 70

3. In a tillage-machine, the combination with the pivoted drag-bar and the pivoted mast from which the drag-bar is suspended, of the pivoted rocker 13, the top flexible connection 14 extending from the upper end of 75 the rocker 13 to the upper end portion of the mast, the chain 15 and the spring 16 extending from opposite ends of the rocker 13, and the hook 17 pivoted to the mast 5 and engaging the convergent ends of said parts 15 and 80 16, substantially as described.

In testimony whereof I affix my signature in presence of two witnesses.

DELBERT E. BARTON.
